MUSTARD DISPENSER

Emile Jeunesse, New Orleans, La., assignor to
Alanna R. Oliver, New Orleans, La.

Application June 15, 1951, Serial No. 231,707

2 Claims. (Cl. 222—227)

1

The present invention relates to a mustard dispenser and it consists in the combinations, constructions and arrangements of parts herein described and claimed.

Generally there is provided a mustard dispenser comprising a substantially cylindrically shaped container having a vertically extending revoluble shaft centrally mounted therein and provided at one side with button-operated means for oscillating the shaft which latter extends through a perforated shelf mounted midway in the container and which is provided with a stirrer immediately above the shelf and with a pair of scraper blades adjacent its lower end. A passageway is provided in the lower end of the container and terminates centrally in the bottom thereof. The passageway extends upwardly at an angle and terminates in a bay which is normally open but which may be closed by a door having angularly disposed guide members thereon. The movement of the scraper blades over the guide members acts to close the door and force the contents which may have accumulated in the bay downwardly through the passage to be dispensed therethrough.

It is accordingly an object of the invention to provide a device of the character set forth which is simple in construction, inexpensive to manufacture, easy to operate, and yet effective and efficient in use.

Still another object of the invention is the provision, in a device of the character set forth, of a novel means for forcing the contents of a container therefrom.

Still another object of the invention is the provision, in a device of the character set forth, of novel means for oscillating a shaft forming a part of the invention.

Other and further objects of the invention will become apparent from a reading of the following specification taken in conjunction with the drawings, in which:

Figure 1 is a vertical elevational view of an embodiment of the invention.

Figure 2 is a sectional view taken along line 2—2 of Figure 1.

Figure 3 is a sectional view taken along line 3—3 of Figure 1.

Figure 4 is a sectional view taken along line 4—4 of Figure 1.

Figure 5 is a fragmentary sectional view taken along line 5—5 of Figure 1.

Figure 6 is a fragmentary sectional view taken along line 6—6 of Figure 1.

Figure 7 is a fragmentary sectional view similar to Figure 1 but showing certain of the parts ad-

2

vanced from their position illustrated in Figure 1.

Figure 8 is a fragmentary perspective view of a scraper mechanism forming part of the invention, and

Figure 9 is a fragmentary perspective view of a follower door forming a part of the invention. Referring more particularly to the drawing, there is shown therein a cylindrical container 10 having a removably mounted relatively thick cap 11 at the upper end thereof and a relatively thick substantially conical bottom 12.

Figure 10 is a fragmentary perspective view of a follower door forming a part of the invention. Referring more particularly to the drawing, there is shown therein a cylindrical container 10 having a removably mounted relatively thick cap 11 at the upper end thereof and a relatively thick substantially conical bottom 12.

A vertically extending shaft 13 is journaled in the top 11, as indicated at 14, and in the bottom 12, as indicated at 15, and, adjacent the upper end of the shaft 13, the same is provided with a gear 16 which is positioned in a recess 17 formed in the cover 11. Extending horizontally into the cover 11 through an outer recess 18 and an inner recess 19 and finally into the recess 17 is a rod 20 provided with a rack 21 upon the inner portion thereof. A compression spring 22 is within the recess 19 and surrounds the rod 20 which is provided with a collar 23 against which the spring 22 is adapted to bear. The rack 21 is enmeshed with the gear 16. Approximately midway upon the inner wall of the container 10 there is provided an inwardly extending annular lip 24 upon which rests a substantially conical shelf 25 which is provided with a plurality of openings 26 in the lower end thereof. Affixed to the shaft 13 is a pair of outwardly extending stirrer blades 27. The stirrer blades 27 are positioned within the shelf 25 and the lower ends of the blades 27 are in close proximity thereto.

Figure 11 is a fragmentary perspective view of a follower door 31 forming a part of the invention. In the bottom 12 there is provided a passageway 29 which extends from a point centrally in the bottom of the member 12 and thence angularly upwardly to a bay 30 which is adapted to be closed by a follower door 31 which is connected by means of a flat spring 32 in turn connected by a rivet 33 or the like to the wall of the container 10. The spring 32 is of a nature to normally urge the door 31 in an upward direction. Each side of the door 31 is provided with a guide member 34 whose upper surface extends downwardly away from the door 31 and the upper face of the bottom member 12 is provided with a pair of recesses 35 which are adapted to receive the guide members 34 when the door 31 is in lowered position.

Figure 12 is a fragmentary perspective view of a follower door 31 forming a part of the invention. Affixed to the shaft 13 adjacent its lower end is a pair of scraper blades 36 each of which is provided with an outwardly extending arm 37 and the lower sides of the blade 36 are in close proximity to the upper side of the member 12.

In operation, it will be apparent that when the

rod 20 is pressed inwardly by the fingers of the user of the device, that the rack 31, being engaged with the gear 16, will act to revolve the shaft 13 against the action of the spring 22 and that when the pressure thereby applied is released the spring 22 acting against the shoulder 23 will return the rod 20 to its normal outward position as viewed in Figure 1 and thereby rotate the shaft 13 in the opposite direction. Thus it will be seen that one pressing of the rod 20 and the release thereof will act to oscillate the shaft 13 and the blades 27 and 36. When this occurs, it will be understood that mustard having previously been placed in the container 10 will be agitated by the blades 27 and a certain portion thereof will fall by gravity through the openings 26. When this occurs the blades 36 and the arms 37 will further stir the mustard contained in the container 10 below the shelf 25 and that as the blades 36 are oscillated the lower ends thereof will come into contact with the angular faces of the guide members 34 to thereby force the door 31 downwardly into the bay 30 to thus forcibly eject through the passage-way 29 any mustard which may have been entrapped therein through previous cycles of operation.

While but one form of the invention has been shown and described herein, it will be readily apparent to those skilled in the art that many minor modifications may be made without departing from the spirit of the invention or the scope of the appended claims.

What is claimed is:

1. A device of the character described comprising a cylindrical container, a top for said container, a bottom for said container having a dispensing opening therein, a vertical shaft centrally disposed in said container and journaled in said top and bottom, agitator blades affixed to said shaft, a perforated shelf mounted upon the inner walls of said container immediately below the agitator blades, scraper blades affixed to the shaft immediately above said bottom, means operable by said scraper blades for forcing portions of the contents of said container through said dispensing opening, and means for

5 oscillating said agitator blades and said scraper blades, said means for forcing portions of the contents from said container including a bay formed in said bottom at the upper end of said opening, a door for said bay, a spring for normally holding said door open, and guide members at each side of said door engageable beneath said scraper blades whereby to force said door into said bay.

10 2. A device of the character described comprising a cylindrical container, a top for said container, a bottom for said container having a dispensing opening therein, a vertical shaft centrally disposed in said container and journaled in said top and bottom, agitator blades affixed to said shaft, a perforated shelf mounted upon the inner walls of said container immediately below the agitator blades, scraper blades affixed to the shaft immediately above said bottom, 15 means operable by said scraper blades for forcing portions of the contents of said container through said dispensing opening, and means for oscillating said agitator blades and said scraper blades, said means including a gear affixed to said shaft within said top, a horizontal rod extending through one side of said top and having a rack formed on its inner portion and engaged with said gear, and a spring in said top for normally forcing said rod outwardly of said top, 20 and said means for forcing portions of the contents from said container including a bay formed in said bottom at the upper end of said opening, a door for said bay, a spring for normally holding said door open, and guide members at each side of said door engageable beneath said scraper blades whereby to force said door into said bay.

EMILE JEUNESSE.
